UNITED STATES PATENT OFFICE

WILLIAM HILL, OF MOUNT VERNON, ILLINOIS.

LATCH AND LOCK COMBINED.

SPECIFICATION forming part of Letters Patent No. 320,472, dated June 23, 1885.

Application filed June 16, 1884. (Model.)

To all whom it may concern:

Be it known that I, WILLIAM HILL, a citizen of the United States, residing at Mount Vernon, in the county of Jefferson and State of Illinois, have invented a new and useful Combined Lock and Latch, of which the following is a specification, reference being had to the accompanying drawings.

My invention relates to a combined lock and latch, and particularly to that class known as "mortise locks;" and it has for its object to provide a device of this character which may be operated as an ordinary latch, and at the same time serve the purpose of a lock; to provide a device of this character which shall be cheap and simple in its construction, and one that will occupy a minimum amount of space.

With these ends in view the invention consists in the improved construction and combinations of parts hereinafter fully described, and pointed out in the claim.

In the drawings, Figure 1 is an elevation of a combined lock and latch constructed in accordance with my invention, the side of the casing being removed to show its interior construction. Fig. 2 is a transverse section on the line *x x* of Fig. 1. Fig. 3 is a view of the inner side of one-half or section of the casing. Fig. 4 is a detail view of the key used with my improved lock, and Fig. 5 is a detail view of the sliding plate for holding the tumblers in position when locked.

In the accompanying drawings, in which like letters of reference indicate corresponding parts in all the figures, A represents the shell or casing, which is provided with the usual opening for the passage of the knob-spindle. This shell or casing A consists of two parts or sections, and one of said sections has cast integral therewith at its forward end a cross-strip, B, having an opening for the passage of the bolt, as will be explained hereinafter. On the inner side of the casing A, near the forward end thereof, upon each side, is formed an offset or shoulder, *b*.

B' represents the bolt, which consists of the side strips, *c*, connected at their ends by a curved portion, *d*, forming shoulders *e*. The sides are connected at their forward ends by means of the bolt-plate C. Extending inwardly from the sides of the bolt, at the forward end

thereof, are shoulders *f*, having inverted V-shaped edges.

D represents a plate which has V-shaped grooves upon its edges, which grooves are 55 adapted to receive the V-shaped edges of the inwardly-extending shoulders *f*.

At the forward end of the plate D is provided an upwardly and a downwardly extending nib, *g g'*, which nibs, when the plate D is 60 pushed forward, are adapted to rest in a recess, *h*, formed upon the rear side of the bolt-plate C.

The plate D is recessed, as shown at *i*, to form a seat for the reception of a flat spring, one end of which bears against a shoulder, *j*, formed 65 by the recessing of the plate D, while the other end extends through the open end of the plate and is seated in a slit, *k*, formed upon the rear side of the bolt-plate.

E represents a sleeve having a rectangular 70 opening for the passage of the knob-spindle. Said sleeve is also provided with outwardly-extending lugs adapted to bear against the shoulders on the bolt. It will be seen that when said sleeve is turned in either direction 75 by the knob-spindle the bolt will be moved rearwardly by one of the lugs of said sleeve.

For returning said bolt to position and holding it in engagement with the keeper on the door-frame, I employ a spring, F, one end of 80 which bears against a shoulder, *k'*, on the bolt, while the other end bears against a nib or lug, *l*, of the casing A.

G represents tumblers, which are pivoted to the inner sides of the casing. These tumblers 85 have openings in their upper ends for the reception of the bit or web of the key, and recesses *m* at their lower ends to receive the nibs of the sliding plate when the bolt is locked, the ends of the tumblers bearing against the 90 bolt-plate and holding it against backward movement.

The operation is as follows: The key is inserted in the opening of the casing and turned. The bit or web of said key engages the openings in the tumblers, the end of the bit or web pushing the sliding plate forward to allow the tumblers to pass the nibs of the same. By the time the ends of the tumblers have nearly passed the nibs the web of the key has left the tumblers and the spring-actuated plate is pressed back, and the nibs thereof engage the seats or

recesses in the tumblers, thus holding them in position and preventing their displacement.

To unlock the bolt, the key is turned in the reverse direction, thus moving the sliding plate forward and allowing the tumblers to be turned from engagement with the nibs of the sliding plate and the bolt-plate.

Having fully described my invention, what I claim as new, and desire to secure by Letters to Patent, is—

The combination, with a suitable casing, of a spring-actuated bolt adapted to slide therein, said bolt having the shoulders *f*, a spring-

actuated plate engaging said shoulders, nibs *g* on said plate, and tumblers pivoted to the inner sides of the casing, said tumblers having recesses or slots at their ends, substantially as set forth.

In testimony that I claim the foregoing as my own I have hereto affixed my signature in presence of two witnesses.

WILLIAM HILL.
